UNITED STATES PATENT OFFICE.

MAURICE E. FAGAN, OF PHILADELPHIA, PENNSYLVANIA.

DESIGN FOR A CASE FOR A VENDING APPARATUS.

SPECIFICATION forming part of Design No. 25,241, dated March 10, 1896.

Application filed September 7, 1895. Serial No. 561,867. Term of patent 14 years.

To all whom it may concern:

Be it known that I, MAURICE E. FAGAN, a citizen of the United States, residing in the city and county of Philadelphia, State of Pennsylvania, have invented and produced a new and original Design for a Case for a Coin-Controlled Vending Apparatus for Stationery, &c., of which the following is a specification, reference being had to the accompanying drawing, forming part thereof.

The leading features of my design for a case for a coin-controlled vending apparatus for stationery, &c., are an upright portion or body with slots and a desk portion which projects outwardly from said upright portion.

In the drawing, wherein the figure is a perspective view of the case of a coin-controlled vending apparatus or slot-machine embodying my design, A designates the upright por-

tion or body of the case of a coin-controlled vending apparatus or slot-machine, and B designates slots in the wall thereof.

C designates a recess or alcove in the wall of the body A.

D designates a ledge or shelf on the side of the body, and E designates a desk portion which projects outwardly from said body portion, but the alcove and ledge or shelf are mere accessories and may be omitted.

What I claim is—

The design for the case of a coin-controlled vending apparatus, substantially as described and shown.

MAURICE E. FAGAN.
